UNITED STATES PATENT OFFICE.

ALFRED RILEY HEATH, OF COVINGTON, INDIANA.

CAR-COUPING.

SPECIFICATION forming part of Letters Patent No. 408,481, dated August 6, 1889.

Application filed April 3, 1889. Serial No. 305,815. (No model.)

To all whom it may concern:

Be it known that I, ALFRED RILEY HEATH, of Covington, in the county of Fountain and State of Indiana, have invented a new and 5 Improved Car-Coupling, of which the following is a full, clear, and exact description.

The object of the invention is to provide a new and improved automatic coupling of simple and durable construction, by means 10 of which cars provided therewith may be coupled to cars having like couplings, or having couplings of the ordinary link-and-pin class.

The invention consists in various novel 15 parts and combinations of the same designed to improve the various features of the coupling, as hereinafter particularly described, and defined in the claims.

Reference is to be had to the accompanying 20 drawings, forming a part of this specification, in which similar letters of reference indicate corresponding parts in all the figures.

Figures 1, 2, and 3 represent front elevations of a car provided with my improved 25 coupling, showing differently-constructed uncoupling devices. Fig. 4 is a perspective view of the draw-head. Fig. 5 is a like view illustrating a modified construction of draw-head hereinafter particularly referred to. Fig. 6 is 30 a longitudinal sectional elevation of the ends of two cars provided with my improved coupling, showing the latter in the coupled position. Fig. 7 is a partly sectional plan view, the couplings being in the position shown in 35 Fig. 6; and Figs. 8 and 9 are respectively an end view and a partly-sectional side elevation illustrating a further modification.

Referring to the parts of the coupling, the draw-head A thereof is provided with a vertical partition A', dividing the draw-head into the longitudinal recesses a a', which are preferably open top and bottom, and through and across both of which extends the axial pin B, which forms in one recess a the pivot for the 40 coupling-hook C, and in the adjoining recess a' forming the coupling-pin with which an opposing coupling-link engages. The recess a is preferably extended a shorter distance back than its companion recess, and is formed 45 with a concaved rear wall a², for a purpose hereinafter explained.

The coupling-hook C, which is pivoted at

its rear end on the pin B within recess a, as specified, is formed with an oblong slot c, through which the pin B passes, and its downwardly and rearwardly extended end c' is weighted to normally maintain the hook in the coupled position, or in position to be coupled. The upper edge of the hook is provided with a rearwardly-disposed hook c², forming a recess c³, the front edge of which hook strikes against the axial coupling pin B of an opposing draw-head in the action of coupling, which causes the coupling-hook to be depressed until the hook c² passes beneath 65 the said opposing coupling-pin, whereupon the weighted end c' of the coupling-hook falls, throwing hook c² upward, the opposing coupling-pin B being received in the recess c³, coupling the cars. The extreme forward end 70 of the coupling-hook C, beyond the hook c² thereof, is formed with a vertical oblong slot c⁴, that is designed to receive the coupling-pin of an ordinary link-and-pin coupling when desired.

The special purpose of the oblong pivot-slot c is to allow the link to be thrown back against the concaved wall a² of the recessed draw-head when the cars are brought together, whereby the pins B will be relieved of 80 all shock.

Referring especially to Fig. 1, which illustrates the uncoupling devices for passenger-cars, D is a rod having a preferably loose connection at its lower end with the weight 85 end of the coupling-hook, which connection is shown in the drawings as a staple-like device d' for the coupling-hook engaging the eye d of rod D. The upper end d² of the rod D is suitably formed to afford a handle to be 90 grasped by the train-hand, and below the upper end d² there is formed on the rod an eye d³, which is adapted to be hooked over any one of a series of upwardly-projecting hooks e on the guard-rail E of the car. By raising 95 the weighted end of the coupling-hook by means of rod D the hook c² of said coupling-hook is thrown out of engagement with the pin B, uncoupling the cars.

In Fig. 2 is illustrated the uncoupling devices preferred for flat cars, said devices consisting of chains F, that are secured to the rear end of the coupling-hook, extending up over pulleys or eyes f to the side of the car,

where, in practice, a series of hooks will be located to be engaged by the chain, whereby the coupling-hook will be held at any desired height to couple onto a higher or lower opposing draw-head.

With a freight-car I prefer the uncoupling devices illustrated in Figs. 3, 6, 7, and 8. In this case a lever G is suitably secured at one end to the coupling-hook, and extends outward in an approximately horizontal direction to or near the sides of the car, and is fulcrumed at or near their center on the lower ends of depending rods G' on the car-body. The rods G are formed at their lower ends with eye or hook g', and the operating-levers G are formed with an elongated loop g², one side or member of which loop rests in the eye or hook g', affording a varying fulcrum-point for the operating-rod to enable the latter to accommodate itself to the vertical movement of the coupling-hook. One of the said operating-levers will be arranged at each side of the car.

The car is provided with a vertical series of downwardly-extending hooks g³, beneath which the lever G is received for maintaining the coupling-hook in a given position.

The draw-head may be formed of bar-iron, if desired, as shown in Fig. 5, in which A² represents a U-shaped bar-iron casing having a partition A', that extends from the front end of the draw-head rearwardly, being bent laterally at its inner end to accommodate a block A³, the forward end a³ of which block is similarly concealed to the corresponding portion of the draw-head shown in the other figures, and for a like purpose. The axial coupling-pin B extends through the ends of casing A² and partition A' and performs the same functions as in the draw-head shown in the remaining figures.

In Figs. 3, 6, and 7, II represents a rubber or other spring-buffer secured to the front platform of the car, which is designed to receive the force of the impact on the cars coming together, the buffers II of opposing cars contacting when the draw-heads are forced back beneath the platforms. The buffers II would of course receive the full force of impact should the draw-heads not buff fairly or be arranged to not project beyond the car-platforms.

A projection I, Fig. 6, is provided on the draw-head to afford an additional or alternative means of coupling the car to the shackle-bar of a locomotive.

In the draw-head is formed a vertical hole a³, through which the ordinary pin of a link-and-pin coupling is passed.

The coupling-hook may be arranged, if desired, to be operated by a cord from the engineer's cab, as indicated at J in Fig. 3.

In Figs. 8 and 9 the draw-head is formed with a recess a⁴ for receiving the weighted end 65 of the coupling-hook when the latter is in the

uncoupled position. In these figures, also, the attachment for operating the coupling consists of a shaft K, journaled beneath the cars, its ends being provided with handles k. Centrally of the shaft is formed the crank portion K', said crank portion extending around the coupling-hook and formed with a loop k', that engages and prevents undue lateral play of the coupling-hook, which hook is provided with a keeper L, that acts as a stop for the loop. By this means the coupling may be operated from either side of the car.

Having thus described my invention, what I claim as new, and desire to secure by Letters Patent, is—

1. In a car-coupling, the combination, with the draw-head formed with a recess having a concaved rear wall a², of a coupling-hook C, having an oblong slot c and pivoted in said recess by a pivot-pin passing through said oblong slot, substantially as described.

2. In a car-coupling, the combination, with the draw-head formed with a partition, forming recesses a a', open at top and bottom, of a pin B, extending across said recess, and a coupling-hook pivoted in recess a by the pin B, the portion of said pin in recess a' affording an engagement for the hook of an opposing coupling-hook, substantially as described.

3. The coupling-hook C, formed with an oblong transverse slot c, weighted rear end c', rearwardly-projecting hook portion c² on its upper edge, and with a vertical oblong slot c⁴ in its forward end, substantially as described.

4. In a car-coupling, the combination, with a recessed draw-head having a pin extending across the recess thereof, of a coupling-hook pivoted in the recess of the draw-head and having a weighted rear end and a vertical slot in its forward end, the hook being adapted to engage the pin of the opposing draw-head and the slot to receive the coupling-pin of an ordinary link, substantially as described.

5. In a car-coupling, a recessed draw-head having the pin B extending across the recess thereof, and the coupling-hook C, provided with the slot c, through which the pin B passes, the weighted rear end c', and the vertical slot c⁴ in its forward end, the hook being adapted to engage the pin of the opposing draw-head, and the slot c⁴, to receive the coupling-pin of an ordinary link, in combination with means for lifting the said hook, substantially as herein shown and described.

6. The combination, with a draw-head, of a weighted coupling-hook pivoted to said draw-head and operating devices for said hook, consisting of the rod G, united thereto and formed with an oblong loop, the said rod being fulcrumed at said loop portion, substantially as described.

ALFRED RILEY HEATH.
